AUTOGRAPHIC REGISTER

Charles W. Potter, Waltham, Mass.

Application December 3, 1938, Serial No. 243,717

10 Claims. (Cl. 282—12)

This invention relates to autographic registers and is exemplified herein in a register of the portable type designed for using stationery in the form commonly known as "fold pack," comprising, as a rule, a multiple strip made up of two or more superposed continuous strips of paper folded zigzag on transverse, weakened lines. These strips are usually provided on one face with printed forms adapted to be filled in for recording sales, orders or other data called for by the particular use to which the register is applied. Transfer material interleaved between the strips reproduces upon the underneath strip or strips whatever is written on the top strip.

The present invention relates more especially to that type of register comprising a container or magazine adapted to hold a suitable supply of fold pack stationery, in which the free end of the multiple strip is drawn out of one end of the container and laid over its top which serves as a writing table and in which the feeding of the strip is accomplished manually by gripping and exerting a pull on its free end to bring the next succeeding set of forms over and upon the writing table, after which the filled-in forms are torn off along perforated lines.

The principal object of the invention is the provision of an autographic register of simple and compact construction, which includes a minimum number of parts and which is efficient and easily operated.

Another object of the invention is the provision of simple and effective means for aligning and registering the forms in a multiple strip on each feeding operation.

A further object is the provision of a construction which permits a register of small size and light weight to be made for use as a portable register.

An additional object is the provision of a portable register which is adapted to handle fold pack stationery in which the bottom strip is of heavier material, such as tag stock.

Another object is the provision in a portable register of an easily accessible compartment in which copies of the filled-in orders or other forms may be temporarily filed as the register is being used.

Other objects of the invention will be in part obvious and in part more specifically described hereinafter.

In its preferred form, my invention contemplates an autographic register comprising a flat container for holding a supply of "fold pack" stationery and having a top adapted to serve as

a writing table and a skeleton cover adapted for exposing the forms on the writing table. The container is open at one end, permitting the end of the multiple strip to be drawn from the magazine and laid over the top of the container, suitable transfer sheets fastened to the top being interleaved with the strips for reproducing upon the underneath forms whatever is written on the top form.

One of the important features of my invention resides in the means provided for registering and aligning the strips on each feeding operation, so that the writing on all the strips will register properly with the printed forms. The preferred form of this means comprises a strip member pivotally mounted in advance of the forward edge of the top of the container and having a thin edge for engaging a fold in the multiple strip to align the parts thereof and to resist feeding. The strip member is held in advanced aligning position by one or more suitable springs, which, however, permit it to be pivotally retracted to open up the fold and release it when a pull of sufficient force is exerted upon the end of the multiple strip. After a fold has been released by a rearward pull, the strip member is returned by the spring to normal position for engaging the next fold in the multiple strip.

Another feature of my invention resides in the provision in the register of a compartment in which may be temporarily filed, for auditing or other purposes, copies of the forms which are filled out during the use of the register. Preferably, this compartment is of shallow form, positioned on the bottom of the register and so constructed as to avoid increasing either the bulk or the weight of the register to any appreciable extent. The compartment may extend a short distance beyond one end of the register to afford a top opening through which the slips may be inserted into the compartment and held therein by its end wall.

In the accompanying drawings showing, for the purposes of illustration, one form of device constructed and adapted to be operated in accordance with my invention, Figure 1 is a perspective view of the manifolding device or register, with one side of the cover broken away to expose the interior construction, the device being shown as in loaded condition and with a set of forms exposed on the writing table ready for use;

Fig. 2 is a vertical, longitudinal, sectional view on line 2—2 in Fig. 1;

Fig. 3 is a cross-sectional view on line 3—3 in

Fig. 2 adjacent the rear end of the device, looking forwardly;

Fig. 4 is a transverse sectional view on line 4—4 in Fig. 2, adjacent the forward end of the device, looking rearwardly;

Fig. 5 is a transverse sectional view on line 5—5 in Fig. 2, looking rearwardly and showing the transfer holding means;

Fig. 6 is a view in perspective of a member adapted for holding the transfer sheet in proper position with a transfer sheet locked thereon;

Fig. 7 is a perspective view of the device, with a portion of the rear of the cover broken away to show the position of the means for holding down the free ends of the strips when moved forward to permit feeding;

Fig. 8 is a transverse sectional view on line 8—8 in Fig. 7;

Fig. 9 is a longitudinal, sectional view of the rear portion of the device on line 9—9 in Fig. 7;

Fig. 10 is a longitudinal, sectional view of the forward portion of the device on line 10—10 in Fig. 7, showing the position of the parts when the fold has been opened up to release it from the fold-retaining member;

Fig. 11 is a perspective view, looking from below, of the register provided with a bottom compartment for temporary filing of copies of filled-out forms;

Fig. 12 is a central, longitudinal, sectional view 30 of the same;

Fig. 13 is a transverse, sectional view on line 13—13 in Fig. 12; and

Fig. 14 is a view in perspective of the rear end of the register, showing the compartment opening.

Referring to the drawings illustrating one embodiment of my invention, there is shown a flat rectangular container or casing adapted to serve as a magazine for holding a supply of stationery in the form of a flat pack. The container comprises a base plate 15 to which is fastened in spaced parallel relation by side plates 16 and 17, a top plate 18 adapted to serve as a writing table (Fig. 1). The top plate is of smaller area than the base and is arranged centrally thereover, and the side plates 16 and 17 on each side are spaced apart for supporting the ends of the top plate. Each of the side plates is provided at its foot with an outwardly turned flange 20 fastened to the base plate by any suitable means such as rivets 21.

The top plate 18 is supported on the top edges of the side plates and is locked thereto by overlapping portions of those edges. At the forward end of the container, the side edges of the top plate overlap the rear top edges of the side plates 16, the forward portions 23 of which extend above the top plate and have rearwardly extending lugs 24 overlapping the upper face of the top plate for locking that end of it to said side plates. The rear side plates 17 support the rear end of the top plate and are provided with rearwardly faced lugs 25 for overlapping and locking that end of the top plate thereto. Beyond the ends of the top plate, the side plates are extended to the ends of the base and their top edges are curved to correspond with the shape of the skeleton cover 26 which is adapted to enclose the container. Between the side plates 16 and 17, the container is open on each side. By means of this construction, the top plate is interlocked on its side edges with the side plates, thereby eliminating the use of other fastening means and producing a structure of extreme simplicity.

The container, at its rear end, is partially 75

closed by various means described hereinafter, but its forward end is entirely open to permit the fold pack supplies to be inserted into the container from that end. A fold pack 30 is shown 5 mounted in the container and the forward end of the multiple strip 31 of the pack is led up around the forward end of the top plate and laid over said plate for writing purposes. Suitable transfer sheets are fastened to the top plate by any suitable means and interleaved between the members of the multiple strip. One means for mounting the transfer sheets, as shown, consists of thin, flexible strips 32 of suitable material, either metal or fiber, having their ends 33 mounted in slots 34 formed in the extended tops 23 of the side plates 16 which serve to hold the strips in stationary position. Each strip carries a carbon sheet 35, the forward end of which is provided with two pairs of longitudinal slits 36 through which the strip is passed, after which the forward edge of the carbon is turned reversely, as shown in Figure 6. This arrangement securely locks the carbon sheet against withdrawal from the strips when the record sheets are pulled rearwardly during the feeding operation.

For aligning and registering the forms on the writing table on each feeding operation, an aligning member 40 is mounted at the forward end of the container parallel to the forward edge of the top plate and in advance of the top plate in position for engaging the bottom face of the multiple strip 31 for breaking it on transverse lines. This member comprises a thin strip having its two ends 41 turned downwardly at right angles and pivotally mounted midway on pins 42 set in the outer faces of the side plates 16. The rocking axis of the member 40, as determined by the pins 42, is parallel to the forward edge of the top plate. Hence the member 40 is always substantially 40 parallel to the forward edge of the top plate. A collar 43 may be mounted on each pin 42 for spacing the arm 41 away from the side plate. Each of the side plates is provided with an oblique open slot 45 and the aligning strip normally lies 45 in the mouths of these slots and in alignment with the upper face of the top plate. To hold the aligning member normally in this position, yet permitting it to be turned rearwardly under stress, one or more helical springs 47 under tension 50 may be applied to the free ends of the arms 41. Preferably, two springs are used, one for each arm, and one end of each spring is fastened to the end of an arm 41 and its other end to a pin 48 in a side plate. In normal position, the 55 forward edge of the strip engages the lower side of the slot which serves as a stop (Fig. 2). The aligning member is so positioned that when it is turned on its pivots in a rearward direction, it moves into proximity to the beveled forward edge 50 of the top plate, as shown in Fig. 10, thereby causing the fold to open up and to be released from said edge.

For holding the fold pack 30 against shifting in the magazine, abutments or stops of any suitable form may be provided for the two ends of the pack, such, for instance, as a U-shaped plate 55 fastened by a screw 56 to the base plate 15 at the rear end of the pack and a U-shaped member 58 at the forward end of the pack (Fig. 3). This latter member is fastened at 59 to the inner face of the forward end of the cover in any suitable manner and is a part thereof (Fig. 2) so that when the cover is removed, the forward end of the container is left open and free of obstruction for permitting it to be loaded. The member 58

is preferably made of thin, flexible strip material so that its rearward arm, which extends upwardly in close proximity to the aligning member 40, may serve as a guide to direct the multiple strip 31 to that member in such manner as to insure sharp folds in the strip at transverse weakened lines (Fig. 2).

For preventing the free end of the multiple strip from curling upwardly, a strip member 60 is mounted transversely the writing table at its rear end (Fig. 1) and in spaced relation thereto. This member is provided with down-turned ends 61 which are fastened to similar down-turned ends of a second strip 63 positioned under the rear end of the table. The ends of the two strips 60 and 63 are, in turn, fastened to a pair of slides 64 loosely mounted in slide-ways formed in the side plates 17 by pressing outwardly the upper edge 65 of each plate which lies between two vertical cuts 66. The slides are held downwardly in the slide-ways by the side portions 67 of the writing table which overlap the top edges of the side plates. A spring 68 under tension, fastened at one end to the struck-out portion 65 and at its other end to the forward end of the slide 64, holds each slide in rearward position, as shown in Figure 1.

For moving the holding member 60 forwardly for permitting the free end of the multiple strip to be gripped by the fingers and pulled rearwardly to bring a new set of forms over the writing table, the strip 63 carries a down-turned finger piece 70, and the writing table is cut at 71 on a half circle. The rear corners of the table 18 are also cut away at 72 to permit forward movement of the holding strip.

The cover 26, which encloses the container, is of skeleton form, open on the bottom and having a rectangular opening 75 in its top adapted to expose the forms on the writing table. The cover has straight sides 76 and curved ends 77 and 78. For fastening the cover to the container, its forward end 77 on its inner face is provided with a pair of clips 79 adapted to hook in around the forward edge of the base 15; and its rear end 78 carries a headed pin 80, the inner end of which is adapted to enter a hole 81 (Fig. 3) in the rear arm 82 of the U-shaped plate 55. The clips 79 are U-shaped, and are fastened at their inner ends each by a screw 83 to the bottom face of a rib 84 on the cover. The pin 80 is mounted loosely in the end 78 of the cover, but is held in forward locking position by a helical spring 85 carried by the pin between the inner face of the cover and a collar 86 on the pin. The bottom edge of the cover, on its sides and rear end, may be rabbeted, as shown at 87 in Figures 2 and 3.

To permit the free end of the strip 31 to be pulled rearwardly when the holding member 60 is moved forwardly, as shown in Figure 7, the top portion of the curved rear end 78 of the cover is depressed to bring its top edge 88 into alignment with the rear end of the writing table and a recess 89 is formed in the end 78 for affording access to the finger piece 70.

In Figures 11 to 14 inclusive of the drawings, the register of my invention is shown as provided with a shallow bottom compartment 92 in which may be placed, from time to time during use, copies of the various forms filled out by the user, these forms being intended to be removed later from the compartment either for auditing, filing, or other purposes. The compartment may be formed in any suitable manner,

but, as shown, it is made from a thin sheet of metal 93, having its side and forward end edges turned upwardly to form side walls 94 and an end wall 95, and then inwardly to form side flanges 96 and an end flange 97 which may be riveted to the bottom face of the base 15, through the holes 98.

Preferably, the sheet 93 is extended beyond the rear end of the base 15 and that end of it is provided with an open central longitudinal recess 100 and with an upturned end flange 101 on each side of the recess. By extending the compartment a short distance beyond the rear end of the register, a top opening is provided through which filled-in forms may be slipped into the compartment, and these forms will be retained therein by the end flanges 101, thereby eliminating any danger of the forms slipping out of the compartment while the register is being used. Since the compartment is somewhat larger in area than the forms filed therein, it may be restricted to approximately the size of those forms by strips 105 right-angled in cross-section, which may be welded or riveted to the sheet 93 (Fig. 13). For holding the forms forward in the compartment, a tongue 106 may be cut out of the sheet and bent upwardly and into right-angled form and its end attached to the bottom face of the base 15 by a rivet 107. The two side strips 105 and the tongue 106 retain the forms in a forward position in the compartment and the recess 100 permits the top and bottom faces of the pile of forms in the compartment to be gripped by the fingers for removing them therefrom.

In use, the register may be placed on a table or counter and for supporting it a slight distance above the support, the base 15 or the bottom plate of the compartment may be provided with rubber tips 110, or the register may be carried around and used as a portable register. To load the register, the cover is removed by withdrawing the pin from the member 55 which releases the rear end of the cover which may then be lifted up and the forward end disengaged from the container. The removal of the cover leaves the forward end of the container open for the insertion of a pack 39 which may be made up of a single strip folded zigzag on perforated lines 112, but is preferably made up of a plurality of superposed strips so folded. The top end of the multiple strip is drawn from the pack around the aligning member 40 until that member engages the first line of perforations in the strip; whereupon, the free end of the strip embracing one set of forms is laid down upon the writing table. Carbon sheets are then interleaved between the strips by lifting up the strips and inserting in the slots 34 strips 32, each carrying a carbon sheet. After the carbon sheets have been interleaved, the cover is then replaced and locked to the container and the register is ready for use.

After the forms on the writing table have been filled in, the operator then presses the finger piece 70 forwardly, moving the holding member in the same direction, which exposes the ends of the forms for gripping with the fingers; after which the forms are drawn rearwardly. The pull exerted on the end of the forms causes the aligning member 40 to turn rearwardly on its pivot into close proximity with the beveled, forward edge of the table, which results in opening up the fold at the perforated lines and releasing the strips from the edge of the aligning member and permitting the strips to be drawn

without appreciable resistance in a rearward direction. As soon as the folds are released from the aligning member, it is turned by the springs back to normal position ready to engage the next fold; and when the next fold engages the aligning member, the operator is informed of this fact by feeling an added resistance to the movement of the strips. By this time, the perforated lines between the used forms and the next adjacent forms on the writing table are at the rearward edge of the holding member and the used forms may be torn off along the perforated lines by utilizing the holding member as a tearing member. If the register is provided with the compartment, then one or more of the copies torn off may be placed therein for future use.

It will be observed that the device of my invention is of simple construction comprising relatively few parts, and that it is simple and positive in operation. The formation of the container by the use of a pair of spaced-apart plates on each side of the container for fastening the top to the base plate provides a simple method of assembly of very low cost. The use of side plates in the form shown permits the top plate to be locked to the side plates without the use of other fastening means and, at the same time, the projecting tops of the side plates at the forward end of the container may be utilized for supporting and holding the members which carry the carbon sheets for providing two or more copies to be made at one time.

It is further to be understood that my invention is not to be limited to the precise form herein shown and described, since it may be shown in various other forms of construction within the purview of the following claims.

What I claim is:

1. In an autographic register, the combination of a flat container adapted for holding a fold pack and having its forward end open and its top adapted to serve as a writing table, an aligning member pivotally mounted at the open end of said container and having a thin edge parallel to the forward end of said top and normally in advance thereof, said edge being adapted for engaging and breaking the multiple strip of said fold pack at transverse, weakened lines when said strip is led around said member and over said writing table, and a spring for holding said aligning member in advanced position yet permitting it, when a pull is exerted on the forward end of said strip, to be pivotally retracted to a position in which said engaging edge is slightly below and closely adjacent to the end edge of said writing table to open up the fold in said strip to release it from said engaging edge.

2. In an autographic register, the combination of a flat container adapted for holding a fold pack and having one end open and its top adapted to serve as a writing table, an aligning member pivotally mounted at the open end of said container and having a thin edge parallel to the end of said top and normally in advance thereof, said edge being adapted for engaging and breaking the multiple strip of said fold pack at transverse, weakened lines when the end of said strip is led around said member and over said writing table, a guide for directing said strip to said member and a spring for holding said aligning member in advanced position yet permitting it, when a pull is exerted on the forward end of said strip, to be pivotally re-

tracted to a position in which said engaging edge is slightly below and closely adjacent to the end edge of said writing table to open up the fold in said strip to release it from said engaging edge.

3. In an autographic register, the combination of a container adapted for holding a pack comprising a continuous strip of paper folded zigzag on transverse, weakened lines, said container having one end open and its top adapted to serve as a writing table, an aligning member pivotally mounted at the open end of said container and having a thin edge adapted for engaging and breaking said strip at transverse, weakened lines when said strip is led around said member and over said writing table, and a spring for holding said aligning member in operative position yet permitting it, when a pull is exerted on the forward end of said strip, to be pivotally retracted to a position in which said engaging edge is slightly below and closely adjacent to the end edge of said writing table to open up the fold in said strip to release it from said engaging edge.

4. In an autographic register, the combination of a container adapted for holding a fold pack and having its forward end open and its top adapted to serve as a writing table, an aligning member pivotally mounted at the open end of said container and having a thin edge parallel to the forward end of said top and normally in advance thereof, said edge being adapted for breaking and aligning the strips of said fold pack at transverse, weakened lines when said strips are led around said member and over said writing table, and resilient means for holding said aligning member in advanced position yet permitting it, when a pull is exerted on the forward end of said strip, to be pivotally retracted to a position in which said engaging edge is slightly below and closely adjacent to the end edge of said writing table to open up the fold in said strip to release it from said engaging edge.

5. In an autographic register, the combination of a flat container adapted for holding a fold pack comprising a continuous multiple strip folded zigzag on transverse, weakened lines, said container being open at its forward end and having a top adapted to serve as a writing table, an aligning member pivotally mounted at the open end of said container and having a thin edge parallel with the forward end of said top and normally in advanced alignment therewith, said edge being adapted for engaging a fold in said strip to resist feeding when the free end of said strip is led around said aligning member and over said top in writing position, and resilient means for normally holding said member in advanced relation to the forward end of said top yet permitting said member to be turned to a position in which said engaging edge is slightly below and closely adjacent to said end edge by a rearward pull on the end of said strip to open said fold and to release it from said member to permit feeding of the strip.

6. In an autographic register, the combination of a flat container adapted for holding a fold pack comprising a continuous multiple strip, folded zigzag on transverse, weakened lines, said container being open at its forward end and having a top adapted to serve as a writing table, an aligning member pivotally mounted at the open end of said container and having a thin edge parallel with the forward end of said top

and normally in advanced alignment therewith, said edge being adapted for engaging a fold in said strip to resist feeding when the free end of said strip is led around said aligning member and over said top in writing position, a guide for controlling the course of said strip to said aligning member to form a sharp fold in said strip, and a spring for normally holding said member in advanced relation to the forward end of said top yet permitting said member to be turned to a position in which said engaging edge is slightly below and closely adjacent to said end edge by a rearward pull on the end of said strip to open said fold and to release it from said member to permit feeding of the strip.

7. In an autographic register, the combination of a flat container adapted for holding a fold pack and having its top adapted to serve as a writing table, an aligning member pivotally mounted at the forward end of said container and having a thin edge parallel to the forward end of said top and normally in advance thereof, said edge being adapted for engaging and breaking the multiple strip of said fold pack at transverse, weakened lines when said strip is led around said member and over said writing table, resilient means for holding said aligning member in advanced position yet permitting it, when a pull is exerted on the forward end of said strip, to be pivotally retracted to a position in which said engaging edge is slightly below and closely adjacent to the end edge of said writing table to open up the fold in said strip to release it from said engaging edge, and a skeleton cover detachably mounted on and enclosing said container.

8. In an autographic register, the combination of a flat container adapted for holding a fold pack and having one end open and its top adapted to serve as a writing table, an aligning member pivotally mounted at the open end of said container and having a thin edge parallel to the end of said top and normally in advance thereof, said edge being adapted for engaging and breaking the multiple strip of said fold pack at transverse, weakened lines when the end of said strip is led around said member and over said writing table, a guide for directing said strip to said member, a spring for holding said aligning member in advanced position yet permitting it, when a pull is exerted

on the forward end of said strip, to be pivotally retracted to a position in which said engaging edge is slightly below and closely adjacent to the end edge of said writing table to open up the fold in said strip to release it from said engaging edge, and a cover detachably mounted on and enclosing said container, and having a top opening for exposing the forms on said writing table.

9. In an autographic register, the combination of a flat container adapted for holding a fold pack comprising a continuous multiple strip, folded zigzag on transverse weakened lines, said container being open at its forward end and having a top adapted to serve as a writing table, an aligning member pivotally mounted at the open end of said container and having a thin edge parallel with the forward end of said top and normally in advanced alignment therewith, said edge being adapted for engaging a fold in said strip to resist feeding when the free end of said strip is led around said aligning member and over said top in writing position, a spring for normally holding said member in advanced relation to the forward end of said top yet permitting said member to be turned toward said end by a rearward pull on the end of said strip to open said fold and to release it from said member to prevent feeding of the strip, and a cover detachably fastened to said container for enclosing the same, said cover having a top opening for exposing the forms on said writing table and having fastened to the inner face of its forward end a guide for controlling the course of said strip to said aligning member to form a sharp fold in said strip.

10. In an autographic register for use with fold packs of paper strips, a flat writing table, means for supporting said table with its forward edge free, a strip aligning member having a thin edge, means for supporting said member so that said thin edge is parallel to said forward edge of the table, spring means normally maintaining said thin edge slightly above the plane of the upper surface of said table a short distance in advance of said forward edge, said aligning member being movable against the force of said spring means to a position in which said thin edge is adjacent to and slightly below said forward edge.

CHARLES W. POTTER.
